B. Langdon,
Making Laths.
Patented Dec. 15, 1835.

Bartholomew Gangdon. 758.

The Schedule referred to in these Letters Patent, and making part of the same, containing a description in the words of the said Bartholomew Gangdon himself, of his improvement, in the Machine for cutting and splitting Laths.

To all to whom these presents shall come.

Be it known that I, Bartholomew Gangdon of the City of Troy in the County of Rensselaer and State of New York, have invented a new and useful improvement in Machinery for Cutting or Splitting Laths and that the following is a full and exact description thereof —

A rectangular frame is to be provided, about eighteen feet long and seven feet wide, more or less. The height of the frame is to be such & the several parts of it with its fixtures and appendages, of such dimensions and materials, and so disposed, as in judgment shall be adapted to the operating part of the Machinery & to the tools as well as to the convenience of attending to and managing the same. The Laths, upon the principle of the improvement, are to be cut or separated from the under edge of a board or plank to be prepared and placed in the machine for the purpose, by means of knives or cutting tools, hereafter to be described. In order to effect this there shall be a cross beam or head block upon the upper part of each end of the frame, with a slot or opening through it from the upper to the lower surface vertically — and its length to an extent a little more than equal to the length of the lath which is to be cut by the machine. This slot, being for the purpose of having the board placed within it, should be near the inside of the cross beam & of such width as to allow the board to drop by its own weight or be easily

pressed down upon guages provided under seats for this lower edge of the board to rest upon as the laths are successively cut or separated from it. Two knives or cutting tools are to be employed in separating each lath from the board. One end of each knife is to be secured to the under side of the head block near the side of the frame, by a screw or pin or other flexible joint, so as to allow the other or inner end to move horizontally one way, or the other up on this joint as the centre of its sweep. The edges of the knives are to be placed outward. & will then act in separating the lath from the board, i.e. by drawing back their inner end from the head block far enough to allow the board to drop down in the slot before the edge of the knives rest upon the guages or rests provided for it, & then having their inner ends forced back 'till the entire length of edge of each knife passes under or a little beyond the slot. & in this way the lath is separated from the board, and when the knives are again drawn back the board will also again drop to its gauge ready for the production of another lath. A steel plate is to be attached to the under side of the head block out side of the slot the inner edge of which, or the lower angle of it being made smooth & of rectangular form is to constitute the lower edge of the slot, on that side against which the knives are to act, they being made to pass under and in contact with it thereby causing the plate to perform in effect the counter part of the cutting process which separates the lath from the board. In order to give the edge of each knife a cutting motion as it cuts off the lath, the blade of the knife (secured by a screw or pin) is to move outwards forward of the line of its edge as to have the screw or pin which secures that end to the steel plate under the head block.

929

pass through it for that purpose, & thus fix the fly wheel just
at a discretionary distance, forward of such line according-
ly. The length of the knives is to be such as to bring the
inner ~~end~~ ^{edge} nearly in contact with each other, as they
pass in together under the head block. In order to give them
the motion required for cutting or separating, ^{the latter} a sliding
bar or beam is to be provided and placed horizontally
in the ~~front~~ centre of the frame, upon fly bars pre-
pared for it, as there may be a cutting apparatus of the
~~the~~ foregoing description, at each end of the frame, &
it being the object of the present improvement to have it
so, this slide should extend in length nearly to each pair
of knives, so as to give effect to both. This is to be done by
giving a reciprocating movement to the slide, in the direction
of its length by means of a crank which shall be made to revolve
near it for that purpose & connecting them together by a shat-
tle bar or sweep, the same being attached to the slide by a
suitable flexible joint, adapted to such operation - and
the same motion is to be communicated to the inner end of the
knives by connecting each to ^{end} of a shuttle bar, while the
other end of the same bar is to be attached to the upper surface
of the slide, both by pin or other flexible joints. The sweep to
be given to the crank and the length of the shuttle bar & also
of those connecting the slide with the knives being sufficiently
indicated by the purposes to be answered by each, they are
here left without further description as matters of judgment
to be exercised in their construction. So also of the moving
power of the machinery and of its application thereto. It may
be by gears bands or otherwise at discretion. In order to ad-
just the edges of the knives to the plate under the head block
a plate of metal may be attached to the upper surface of each
end of the slide through which an adjusting screw may be let
down so as to bear against the under side of the blade or plate.

of each knife, the outer ends of which in its connection with the shackle bar being brought on to the end of the slide sufficient for that purpose. In this way the knife may be raised or depressed, as occasion shall require. So also the gauges on which the board rests, as it drops down in the slot before the knives, being made elastic, may in like manner be ~~raised~~ ^{eliminated} or depressed by means of a screw passing through a fixture of the frame against the under side of each gauge and the thickness of the lath thereby regulated. As an alternative improvement, instead of two knives at each end of the frame, as above described, for cutting or separating each lath, one knife or cutting tool only may be used. In which case, its outer end being like the other attached to the plate of the head block near the side of the frame & the length of the knife being equal to the length of the lath to be cut by it, the other end is to be operatively in the same manner, or upon the same principles. One of such single knives being fixed at each end of the frame, & like the double knives connected with the slide, it is obvious that in either case a lath will be produced at each reciprocating movement thereof, one at each end alternately. The knives or cutting tools, except about four inches wide of the blade or edges, may be of cast iron, suitably prepared, and the blade attached thereto by screws or otherwise. For a further illustration of my invention, I refer to the model & drawing of the same deposited in the patent office. What I claim as my own invention, and not previously known in the above described machine, is the machine it-self and the manner of cutting lath as above specified and exhibited.
